CLAIM

I claim the ornamental design for an electronic pillbox, as shown and described.

DESCRIPTION

FIG. 1 is a top plan view of an electronic pillbox showing my new design;

FIG. 2 is a front elevational view thereof;

FIG. 3 a bottom plan view thereof;

FIG. 4 is a rear elevational view thereof; and,

FIG. 5 is a left side elevational view thereof, the right side elevational view being a mirror image thereto.
